UNITED STATES PATENT OFFICE

2,191,489

REEL

Frederick B. McQuiston, Pittsburgh, Pa.

Application December 15, 1938, Serial No. 245,968

4 Claims. (Cl. 242—74)

This invention relates to reels, and its general object is to provide a reel that is primarily designed for use with moving picture film, or other strip material such as tape or the like, and which includes means for attaching the end of the film to the hub of the reel in a manner whereby the film will be held against casual removal or displacement while winding yet will become automatically released when unwound and without breakage to the film.

A further object is to provide a reel including a film holding device which makes it possible to attach the film to the hub instantly, and without bending the end of the film as is necessary in the use of ordinary reels of this character, therefore breaking or otherwise damaging the film when being applied or becoming detached from my reel is practically impossible.

Another object is to provide a film holding device that can be applied to reels now in general use without any material change to the structure thereof, or the die set-up of stamping machines or the like used in manufacturing the same.

A still further object is to provide a reel including a holding device of the character set forth, that is simple in construction, inexpensive to manufacture, and extremely efficient in operation, use, and service.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:

Figure 1 is a sectional view taken approximately on line 1—1 of Figure 2, looking in the direction of the arrows.

Figure 2 is a sectional view taken approximately on line 2—2 of Figure 1, looking in the direction of the arrows.

Figure 3 is a fragmentary vertical sectional view illustrating the film attached to the reel and the position assumed by the holding device immediately upon movement of the reel for winding the film thereon.

Figure 4 is a sectional view taken approximately on line 4—4 of Figure 3, looking in the direction of the arrows.

Figure 5 is a perspective view of a modified form of my holding device.

Referring to the drawing in detail, the refer-

ence numeral 1 indicates the side plates or disks of the reel and which are secured together in reel formation by a hollow cylindrical hub 2 having a relatively wide axially arranged slot 3 therein, extending throughout its width for the purpose of receiving the end of the strip material therein, such as the film A as shown, the film being provided with the usual perforations B therein.

From the foregoing, it will be apparent that the reel structure is substantially identical to that of reels now in general use, with the single exception that the slot 3 is wider than the usual film receiving slots. However, the important feature of my reel lies in the film holding device which is in the form of a toggle including a flat lever 4 preferably of a width substantially co-extensive with that of the hub and one edge portion of the lever is rolled upon itself about a pivot pin 5 to provide trunnions mounted in bearing openings in the disks 1, for rocking movement of the device from one side edge of the slot to the opposite side edge as will be apparent upon inspection of Figures 2 and 3.

Secured to the opposite or outer edge portion of the lever 4 is a wing member 6 that includes a central arcuate portion merging into outwardly flared curved wings 7, the wing member being fixed to the lever 4 midway its ends as shown, and the arcuate portion is provided with openings for the passage of perforation receiving studs 8 formed on the outer edge of the lever which is of a length so that the studs project a suitable distance beyond the slot 3 for disposal in the path of the perforations B when the end of the film is inserted in the slot, as shown in Figure 3.

In the use of my reel for moving picture film, it will be obvious that the reel is applied to the picture projector shaft or spindle, the side walls or disks 2 of the reel being provided with the usual centrally disposed openings C for that purpose, then the end of the film is threaded in the slot 3. Upon manually turning the reel, in the direction the film is to be wound, that is counter-clockwise in Figure 3, the studs will seat themselves within the perforations and cause the holding device to move on its pivot to the position for engagement with one edge of the slot, as shown in Figure 3, from which it will be readily seen that the studs hold the film against casual removal or displacement from the holding means, but when the film is unwound, it will be instantly released from the studs and without possibility of breakage or damage to the film.

While I have illustrated a holding device that

includes a pair of studs, only one stud or any number may be employed, it depending of course upon the character of the material for which the reel is to be used, that is the number of perforations in the material. Again, the wings may be of a length to engage the inner surface of the hub so as to clamp the material between the edges of the wings, and the hub, as will be apparent. That feature is important, in the event the material is very thin and unperforated.

In Figure 5 I have illustrated a modified form of my device that is made from a single blank of material shaped to provide a wing member having arms 9 formed on and extending centrally at right angles from the sides of the arcuate portion 10 for disposal in parallelism with each other between the wings 11, and extending through the outer ends of the arms 9 is a pivot pin 12 to be mounted in the side plates or disks 1 of the reel for positioning this form of the device with respect to the slot 3 in the same manner as that of the form of Figures 1 to 4. The perforation receiving studs of the form of Figure 5 are struck from the arcuate portion thereof as shown, and are indicated by the reference numeral 13.

It will be obvious that the form of Figure 5 is capable of performing all the functions of the other form, but will make it possible to manufacture the device by a simplified and inexpensive method, as the blanks can be stamped from a single sheet of material, as will be apparent.

It is thought from the foregoing description that the advantages and novel features of the invention will be readily apparent.

It is to be understood that changes may be made in the construction and in the combination and arrangement of the several parts, provided that such changes fall within the scope of the appended claims.

40 What I claim is:

1. A reel comprising sides, a hub secured to said sides and having a slot therein for the pas-

sage of one end of perforated material to be wound upon the reel, means pivotally mounted within the hub and including studs projecting through said slot to be received in the perforations of the material for releasably attaching 5 said end of the material with respect to the hub.

2. A reel comprising sides, a hub secured to said sides and having a slot therein for the passage of an end of perforated material to be wound upon the reel, a lever pivotally mounted within 10 the hub, a winged member secured to the lever to be carried thereby for movement across the slot and having the wings thereof arranged in the path of said end of the material, and studs on said winged member and receivable in the 15 perforations of said material.

3. A reel comprising sides, a hub secured to said sides and having a slot therein for the passage of an end of perforated material to be wound upon the reel, a lever pivotally mounted within 20 the hub, a winged member including an arcuate central portion secured to the lever to be carried thereby for movement across the slot and the wings thereof being outwardly flared in curved formation from the arcuate portion for 25 disposal in the path of said end of the material and studs on said arcuate portion and extending through the slot to be received in the perforations of said material.

4. A reel comprising sides, a hub secured to 30 said sides and having a slot therein for the passage of an end of perforated material to be wound upon the reel, means pivotally mounted in the hub for releasably attaching said end of the material with respect to the hub and being formed 35 from a single blank of material shaped to provide a winged member, arms formed on the sides of the winged member, a pivot pin extending through the arms and having its ends mounted in the sides of the reel and studs struck from the 40 winged member and extending through the slot to be received in the perforations of said material.

FREDERICK B. McQUISTON,
